UNITED STATES PATENT OFFICE.

GUSTAV ADOLPH HUNDEWADT, OF HAMBURG, GERMANY, ASSIGNOR TO THE FIRM
WALDHEIMER PARFUMERIE- UND FEINSEIFEN-FABRIK A. H. A. BERGMANN, OF
WALDHEIM, SAXONY, GERMANY.

CYLINDRICAL CASE FOR HOLDING SHAVING SOAP AND SIMILAR OBJECTS.

Application filed March 11, 1925. Serial No. 14,754.

To all whom it may concern:

Be it known that I, GUSTAV ADOLPH HUNDEWADT, a citizen of the German Republic, residing at Hamburg, Germany, have invented certain new and useful Improvements in and Relating to Cylindrical Cases for Holding Shaving Soap and Similar Objects, of which the following is a specification.

10 The invention refers to improvements in the cylindrical cases for holding sticks of shaving-soap and similar objects, and more particularly spoken it concerns the inner parts of such cases, the upper brim of which, 15 by having a plurality of longitudinal slits, is provided with resilient tongues, adapted to hold the soap-stick or the like by pressing on it. It has been found however, that the inwardly pressing resiliency of those tongues 20 is often either too strong or too weak, to fit for the particular stick of soap or the like contained in the case.

Those inconveniences are overcome according to my present invention by arranging the upper slit brim of the inner parts with a somewhat conical outer surface and by providing a corresponding conical ring or ferrule adapted to be slipped over the brim and to compress its tongues more and 30 more, the deeper the ring is slipped. In the practical execution of the invention the brim and the ring to be slipped over it may be provided with screw-threads, for the purpose of preventing the ring from slipping off the brim, if the latter has turned to be slippery by the soap or other contents of the case. Another advantage of the new construction according to my invention consists therein, that an equal pressure of the 40 tongues or parts of the slit case on the soap-stick or the like is obtained, even if the outer circumference of the soap-stick is not quite regular or if the diameter varies. Further it is possible, to provide a cylindrical brim beyond the screw-threaded part of the ferrule or screw-nut, which flat brim, by covering the slit ends of the case, makes it 45 possible, to use up the soap-stick to its last end, without being hurt by the sharp corners of the tongues.

In the drawings I have shown a longitu-

dinal section through a preferred embodiment of the invention.

The cylindrical case consists in the lower part *a* and the upper part or lid *b*, the latter being adapted to be slipped over the former, to which effect it is advisable, to provide the lower part with a narrowed upper shoulder upon which the lid *b* is adapted to rest. The upper brim *c* of the lower part 60 of the case is provided with longitudinal slots *d*, and further it is made conical; besides that it is provided with a screw-thread *e*, which may be pressed into the sheet-metal forming the case. On this 65 thread is screwed a screw-threaded ring or ferrule *f*, which has the same conical shape as the brim *c* of the lower case *a*. In the shown construction I have provided small cylindrical parts above and below the screw-threaded conical parts of the lower case and the surrounding ring *f*. The cake or stick of the soap *g* has about the same diameter 70 as the upper cylindrical end *c* of the case *a*, so that by screwing the ring *f* down on 75 the thread *e* of the case *a*, the tongues *d* are narrowed, so as to press on the soap-stick and to hold it in the desired height. By screwing off the ferrule or ring *f*, the clamping connection is loosened and the soap-stick 80 is released.

I claim:

In a case for holding sticks of shaving soap and the like, the combination of a lower case or receptacle, the upper portion reduced 85 and defining an annular shoulder to support the lid of the case, and a cylindrical portion extending upwardly from said shoulder and a plurality of convergent resilient tongues extending from such cylindrical portion, said tongues having an externally threaded portion, a clamping ring presenting an internally threaded conical portion adapted to be associated with the threaded portions of the tongues whereby 90 to force the free ends of the tongues into smooth clamping relation with the soap stick, and an upper case or lid seated on said annular shoulder.

In testimony whereof I have affixed my 100 signature.

GUSTAV ADOLPH HUNDEWADT.
